DISPOSABLE INFANT'S NURSING BOTTLE

William P. Garred, Onawa, Iowa

Application June 28, 1956, Serial No. 594,659

7 Claims. (Cl. 215—11)

My invention relates to a disposable infants' nursing 15 bottle.

An object of my invention is to provide a nursing bottle which is made of inexpensive material and which can be discarded after use, thereby not requiring all of the attendant re-sterilization of glass bottles and the like.

A further object of my invention is to provide a construction which is rigid enough for the infant to handle or hold and which includes further means whereby the bottle can be easily and readily filled with milk.

A further object of my invention is to provide a device of this character which is of relatively simple construction.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a sectional view taken longitudinally through the arrangement in its filling position,

Figure 2 is an enlarged detail,

Figure 3 is a further enlarged detail,

Figure 4 is a further enlarged detail, and

Figure 5 is a forward elevation of the bottle ready for use.

My invention contemplates the provision of an infants' milk bottle whereby after use, the major portion of the bottle can be discarded and whereby certain other portions can be used over and over again, this feature thereby providing a great many advantages of sanitation and without requiring the usual cumbersome re-sterilization of bottles and other operations.

I have used the character 10 to designate the nipple end of the bottle which includes the small openings 11, these openings 11 being sealed by means of the adhesively attached member 12 terminating in the tab 13.

The nipple 10 extends into the further portions 14 which gradually merge with the extremely thin or attenuated cylindrical portion 15. The nipple and the portion 15 is preferably made of an inexpensive plastic, such as vinyl plastic, and attached over each side of the cylindrical member 15 at the upper terminals thereof are the pair of metal foil or other channel members 16 which include the pairs of extending tabs 17 at either side thereof.

The character 18 indicates a cylindrical aluminum member or support having the annular shoulder at 19 upon which rests the shoulder portion 20 which is an integral part of the nipple portion 14. It will be observed from Figure 1 that the upper end of the cylindrical member 15 is completely open and is ready for the pouring operation. The infant's milk meanwhile has been prepared in any large vessel to the proper temperature and other requirements, and it will be noted that in this position the member 15 can be filled practically full of milk. Receiving the member 15 is a rigid further cylindrical plastic member 21 which provides rigidity to the

2

arrangement, and the arrangement is thus quickly and easily filled.

After filling nearly to the top, the tabs 17 are grasped and are rotated about their longitudinal axes, whereby the 5 end of the member 15 will appear as in Figure 2, thereby providing a very tight seal at this point. One of the tabs 17 is then bent backwardly over the top of the member 15 (see Figure 3) and the other tab is bent downwardly into a vertical position as shown and adjacent to the 10 tubular member or shell 21.

I provide a resilient rubber cap member 22 having the resilient cylindrical side wall 23 which is pressed down firmly as clearly shown in Figure 3, thereby securing this end of the infant's bottle, and the flaps 17.

The member 21 and the enclosed bottle are then taken out of the member 18 and reversed and will then occupy the position shown in Figure 5 and the member 12 is then torn off by means of the tab 13. The bottle can then be stored in the refrigerator, and if it is desired to maintain the contents completely sealed the tab 12 can be left on.

The entire device including the outer member 21 and the inner casing with the nipple can then be handed to the infant, the member 21 providing the required rigidity.

25 After use the member 15, member 10, etc. are removed by removing the cap 22, and these parts can be thrown away, these portions being cheap enough so that a great many can be purchased at one time. These portions should also be supplied in sterilized containers or wrappings when sold to provide complete sanitation.

It will also be noted that several of the bottles can be filled at one time and then stored.

It will now be noted that I have provided the advantages mentioned in the objects of my invention with other advantages being readily apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A disposable infants' nursing bottle comprising an outer rigid substantially cylindrical shell, an inner collapsible milk receiving container including an end nipple portion, said container being adapted to be received in said outer shell, said container being made of relatively cheap disposable material, and including an upper portion including a pair of substantially stiffened strips attached along the upper edges thereof, whereby said strips can be rotated about their longitudinal axes to seal said container after filling, said strips having extending tabs, one pair of which is received on the periphery of said shell, the other pair of which is bent over the closed

55 end of said container, means for securing said tabs and said container including a resilient cap resiliently received over the end of said shell.

2. A disposable infants' nursing bottle comprising an outer rigid substantially cylindrical shell, an inner collapsible milk receiving container including an end nipple portion, said container being adapted to be received in said outer shell, said container being made of relatively cheap disposable material, and including an upper portion including a pair of substantially stiffened strips attached along the upper edges thereof, whereby said strips can be rotated about their longitudinal axes to seal said container after filling, said strips having extending tabs, one pair of which is received on the periphery of said shell, the other pair of which is bent over the closed

60 end of said container, means for securing said tabs and said container including a resilient cap resiliently received over the end of said shell, said nipple including openings,

an adhesively attached member for sealing said openings, means for receiving said shell and said container for milk filling position comprising a further substantially cylindrical outer member including an inner annular shoulder upon which portions of said container will rest in inverted position.

3. In a disposable nursing bottle, the combination which comprises a tubular support having a shoulder spaced downwardly from the upper end, a tubular shell positioned in and extended upwardly from said support, a container of inexpensive disposable material having a nipple portion on the lower end positioned in said shell, and means for closing the end of the container opposite to the end upon which the nipple portion is positioned.

4. In a disposable nursing bottle, the combination which comprises a tubular support having a shoulder on the inner surface and spaced downwardly from the upper end, a tubular shell positioned in and extended upwardly from said support, a container of inexpensive disposable material having a nipple portion on the lower end positioned in said shell and extended upwardly therefrom, closure means in the end of the container opposite to the end on which the nipple portion is positioned, and a cap of elastic material positioned over said closure means substantially sealing said container.

5. In a disposable nursing bottle, the combination which comprises a tubular support having a shoulder on the inner surface and spaced downwardly from the upper end, a container of inexpensive disposable material having a nipple portion with an aperture therein on one end positioned with the nipple portion in said support, said container being retained in an upright position by the shoulder of said support, a piece of adhesive tape positioned over the aperture of the nipple, a pair of channel members on the edges of the sides of the container at the end opposite to the end on which the nipple portion is positioned, said channel members having tabs extended at the ends and said tabs being rolled to seal the con-

tainer, and a cap of elastic material positioned over the channel members for retaining the end of the container sealed.

6. In a disposable nursing bottle, the combination which comprises a tubular support, a container of inexpensive disposable material mounted in an inverted position in the tubular support and having a nipple on the lower end, means in the support for holding the container in an upright filling position and with the lower end of the nipple spaced upwardly from the lower end of the tubular support, the end of the container opposite to the end on which the nipple is positioned being open, and a resilient cap member designed to be secured over the open end of the container for sealing the end of the container.

7. In a disposable nursing bottle, the combination which comprises a tubular support, a container of inexpensive disposable material freely mounted in an inverted position in the tubular support and having a nipple on the lower end, means in the support for holding the container in an upright filling position with the lower end of the nipple spaced inwardly from the lower end of the tubular support, strips of material having adhesive thereon on the end of the container opposite to the end on which the nipple is positioned, and a resilient cap member secured by the strips of material to the end of the container for sealing the container.
